UNITED STATES PATENT OFFICE.

WILLIAM A. BUTCHART, OF DENVER, COLORADO.

MECHANICAL MOVEMENT.

1,367,117.

Specification of Letters Patent.

Patented Feb. 1, 1921.

Application filed March 19, 1919. Serial No. 283,524.

To all whom it may concern:

Be it known that I, WILLIAM A. BUTCHART, a citizen of the United States, residing at Denver, in the county of Denver and State 5 of Colorado, have invented certain new and useful Improvements in Mechanical Movements, of which the following is a specification.

This invention relates to mechanical 10 movements of the type used to impart a reciprocating motion to a movably mounted element such as a screen or concentrating table.

It is the primary object of my invention 15 to provide a movement of this character which by centrifugal action upon a rotary body, actuates an oscillatory support upon which the body is mounted, against the yielding resistance of an elastic buffer and 20 thereby imparts a differential reciprocating motion to the table or other appliance connected with the support.

An embodiment of my invention has been 25 illustrated in the accompanying two sheets of drawings in which like characters of reference designate corresponding parts throughout the several views and in which—

Figure 1 represents a plan view of the 30 mechanical movement,

Fig. 2, a fragmentary and partially sectional side elevation of the same, and

Fig. 3, a partially sectional front elevation of the movement looking in the direction of the arrow A, Fig. 2.

The reference character 2 designates the 35 base of a chair 3 upon which the reciprocating transmission members of the movement is slidably supported. A pillow-block 4 at the forward end of the base supports a 40 rocker shaft 6 the end portions of which project beyond the same.

Upwardly extending rocker arms 5 fastened upon the projecting portions of the shaft by set screws 7, carry in bearings at 45 their upper ends, a second shaft 8 for the support of a rotary pulley 9. A yoke 10 which straddles the pulley is loosely connected with the shaft at opposite sides thereof, and a rod 12 fastened to the yoke passes 50 through openings in the chair for its connection with the table, screen or other driven element to which the movement is applied.

The element has been designated in Fig. 55 1 of the drawings by the reference character 13, and it is fastened to the rod through the

instrumentality of a pair of clamping nuts 14 which are screwed upon the threaded end portion of the same.

The chair has at its top a bearing 15 and an abutment 16 opposite thereto, which are 60 provided with aligned openings for the passage of the connecting rod of the transmission member and it has between the bearing and the abutment, a hollow to receive the headed portion of a buffer block 17 which 65 loosely surrounds the connecting rod and is slidably supported in the bearing 15, and a buffer spring 23 which is coiled around the rod between the block and the abutment.

The transverse portion of the yoke of the 70 transmission member is shouldered to engage the end of the buffer block projecting through the bearing of the chair and a coiled spring 18 placed around the rod between the abutment and the adjustable collar 19 on 75 the rod serves to yieldingly oppose the forward motion of the transmission member by the oscillating movement of the support with which it is connected.

The collar is adjusted for the purpose of 80 regulating the pressure of the spring, by a nut 20 which is screwed upon the threaded end portion of the rod to which the before-mentioned clamping nuts 14 are applied.

The pulley 9 which is mounted for rotation on the shaft 8 carried upon the rocker arms, has an eccentric unbalanced weight 21 which when the pulley is rotated by a belt-connection with a conveniently located motor, tends to displace its axis of rotation 90 under the influence of centrifugal force.

In the operation of the movement, a rotary motion of the pulley in the direction of the arrow B, Fig. 2, will cause the rocker arms on which the pulley is supported to 95 move forwardly about the axis of oscillation of their shaft by the centrifugal force acting upon the unbalanced weight. The forward motion of the arms causes the yoke to separate from the buffer block by compression of the spring 18 and when during the second half of the revolution of the pulley, the weight has passed the perpendicular, the expansion of the contracted spring aids in compelling the oscillatory support 105 to move in the opposite direction.

The return movement of the support beyond its center of oscillation, brings the yoke in contact with the buffer 17. The impact of the transmission member with the 110

sliding buffer compresses the buffer spring 23 which in consequence absorbs the momentum of the moving body and limits the movement thereof and by subsequent expansion aids in reversing its motion when the unbalanced weight again passes the perpendicular passing through its center of motion.

It will thus be seen that by imparting a continuous rotary movement to the pulley, the transmission member and the therewith connected concentrating table or other driven element receive a differential reciprocating motion requiring the expenditure of but little mechanical energy.

In order to prevent the obviously objectionable engagement of the head of the buffer block with the bearing in which it is supported, during each forward motion of the oscillating element a resilient washer preferably made in the form of a light coiled spring 22 is placed between the head of the buffer and the bearing to cushion its return stroke.

Having thus described my invention what I claim and desire to secure by Letters-Patent is:

1. A mechanical movement comprising an oscillatory support, a rotary unbalanced pulley thereon, a transmission-member mounted for reciprocation, in connection with the support, a stationary abutment, a spring bearing on the abutment and acting upon the transmission member to yieldingly resist the movement of the support in one direction, a sliding buffer disposed to be engaged by the member during movement of the support in the opposite direction, a spring to resist the movement of the buffer by the impact of the member, and a spring cushioning the return movement of the buffer.

2. A mechanical movement comprising an oscillatory support, a rotary unbalanced pulley thereon, a transmission-member mounted for reciprocation, in connection with the support, a stationary abutment, a spring bearing on the abutment and acting upon the transmission member to yieldingly resist the movement of the support in one direction, a sliding buffer disposed to be engaged by the member during movement of the support in the opposite direction, and a spring to resist the movement of the buffer by the impact of the member.

3. A mechanical movement comprising a base, an oscillatory support thereon, a rotary unbalanced pulley on the support, a chair on the base having a bearing, an abutment, and alined openings therein, a hollow buffer sliding in the bearing, a spring between the buffer and the abutment, a rod slidably extending through the buffer and the opening of the abutment, a connection between the rod and the support, adapted to engage the buffer during movement of the

support in one direction, a collar on the rod, and a spring between the collar and the abutment to yieldingly resist the movement of the support in the opposite direction.

4. A mechanical movement comprising a base, an oscillating support thereon, a rotary unbalanced pulley on the support, a chair on the base having a bearing, an abutment, and alined openings therein, a hollow buffer sliding in the bearing, a spring between the buffer and the abutment, a cushion spring between the buffer and the bearing, a rod slidably extending through the buffer and the opening of the abutment, a connection between the rod and the support, adapted to engage the buffer during movement of the support in one direction, a collar on the rod, and a spring between the collar and the abutment to yieldingly resist the movement of the support in the opposite direction.

5. A mechanical movement comprising a base, a pillow block thereon, a rocker shaft in the pillow block, upwardly extending arms on the shaft, a shaft supported at the upper ends of the arms, a rotary unbalanced pulley on the upper shaft, a chair on the base having a bearing, an abutment, and alined openings therein, a hollow buffer sliding in the bearing, a spring between the buffer and the abutment, a rod slidably extending through the buffer and the opening of the abutment, a connection between the rod and the support, adapted to engage the buffer during movement of the support in one direction, a collar on the rod, and a spring between the collar and the abutment to yieldingly resist the movement of the support in the opposite direction.

6. A mechanical movement comprising in combination with a reciprocatory element, an oscillating support, a rotary unbalanced pulley thereon, a bearing, an abutment opposite thereto, a buffer on the bearing, a rod connecting the support and the reciprocatory element, and sliding through the bearing and the abutment, a spring between the abutment and the buffer, a collar on the rod, and a spring between the abutment and the collar.

7. A mechanical movement comprising in combination with a reciprocatory element, an oscillating support, a rotary unbalanced pulley thereon, a bearing, an abutment opposite thereto, a buffer composed of a sleeve sliding on the bearing, and a spring opposing a movement of the sleeve, a rod sliding through the sleeve and the abutment and connecting the reciprocatory element to the support, a spring between the abutment and the buffer-sleeve, a collar on the rod, and a spring between the abutment and the collar.

In testimony whereof I have affixed my signature.

WILLIAM A. BUTCHART.
